KARL WILHELM MAUSER, OF WALDECK, GERMANY

REINFORCING MEANS FOR THE RIMS OF OPENINGS IN METAL CONTAINERS

Application filed September 22, 1930, Serial No. 483,632, and in Germany September 27, 1928.

It is known to secure collars to the rims of openings in metal vessels and containers by means of two seamed rings, one of which is formed from the wall of the container and the other consists of a rib on the collar, the two rings being united to form a simple folded rib. In this construction, the rim collar is suspended freely from the folded rib and is subjected to heavy stress during opening and closing as well as when the container is being rolled along the ground. There is thus the risk of the folded seam being opened more or less considerably and of the collar being thereby twisted, thus rendering it difficult, if not impossible, to withdraw the stopper or plug.

In order to prevent twisting of the collar in rim openings in which the collar is secured in a different manner, it has also been proposed to allow the flange of the collar, which initially is of polygonal shape, to engage so as to fit in a flange formed out of the container wall.

The present invention consists in a combination of the above two known features, with the result that by imbedding the rim collar in the previously drawn flange of the container wall, the folded rib is relieved of the duty of acting as carrier for the rim collar, so that opening out of the folded seam by blows or pressure does not occur and the securing of the rim bush itself can be easily effected and is secure. The invention may also be so carried out that a ring is fitted into the folded rib which ring has a number of peripheral leading eyes or the like.

The invention is illustrated by way of example in the accompanying drawing, which shows an elevation, partly in section, of two constructional forms of rim collar securing arrangement.

Referring to Figure 1, *a* is the collar of the rim opening in the container, for instance a bung hole, with the fold ring *c* provided on the collar *b*. The fold ring is united with a fold ring *f* formed by drawing it out of the container wall *d* to form a simple folded rib. In the construction according to Figure 2, a ring *g* provided with leading eyes *g¹* is fitted in with the folded rib.

What I claim is:—

1. The combination with a sheet metal container having an opening in a wall thereof, of a collar fitted in the opening, a polygonal shaped peripheral flange on the collar, an uninterrupted fold ring on the collar, the container wall having an outwardly extending flange surrounding the opening and terminating in an uninterrupted fold ring adapted to cooperate with the fold ring of the collar to provide a seam connection between the container wall and the collar, the flange of the collar extending beyond the outer end of the fold ring carried thereby and having intimate engagement with the flange of the container for its entire width. 60

2. Means for bushing openings in metal vessels or containers, including a bush having an annular ring and a polygonal flange extending beyond the periphery of said ring, 70 said container having a socket formed therein adapted to receive the polygonal flange to prevent rotation thereof when inserted, an uninterrupted annular flange on the container extending from the bottom of said 75 socket so as to encircle the ring on the bush, said annular flange being folded over the ring and the ring then folded simultaneously with the flange to overhang the bush to secure the bush to the container. 80

In testimony whereof I have signed my name to this specification.

KARL WILHELM MAUSER.
